Primary Examiner — Patricia A Palasik(74) *Attorney, Agent, or Firm* — Alan D. Kamrath; Mayer & Williams PC(57) **CLAIM**

The ornamental design for a soldering bit, as shown and described.

DESCRIPTION

FIG. 1 is a perspective view of a soldering bit showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the soldering bit in which the design is embodied that are not considered part of the claimed design.

1 Claim, 7 Drawing Sheets(56)
